(57) **CLAIM**

The ornamental design for a pick-up cartridge, as shown and described.

DESCRIPTION

FIG. 1 is a top, front, right side perspective view of a pick-up cartridge, showing the new design;

FIG. 2 is a bottom, front, right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

Evenly broken lines depict portions of the pick-up cartridge which form no part of the claimed design.
